UNITED STATES PATENT OFFICE.

JASPER M. MADDING AND BENJAMIN F. WATSON, OF BRIDGEPORT,
ILLINOIS.

FENCE-POST.

SPECIFICATION forming part of Letters Patent No. 390,495, dated October 2, 1888.

Application filed June 29, 1888. Serial No. 278,539. (No model.)

To all whom it may concern:

Be it known that we, JASPER M. MADDING and BENJAMIN F. WATSON, citizens of the United States, residing at Bridgeport, in the county of Lawrence and State of Illinois, have invented certain new and useful Improvements in Fence-Posts, of which the following is a specification, reference being had therein to the accompanying drawings.

10 Our invention relates to certain new and useful improvements upon metallic fence posts; and it has for its objects to provide an extremely simple post, that may be easily rolled and formed into shape, and which, when erected, will be very firm and durable and permit of the attachment to it of either the wires of a wire fence or the rails of a board fence, as may be desired; that may be provided with an integral anchoring device to hold it firmly and 15 prevent its withdrawal from the earth, and which will be comparatively light, and yet possess sufficient strength to permit it to be driven into the earth without the necessity of making an excavation for its reception, as will be more 20 fully hereinafter set forth, and particularly pointed out in the claims appended.

The invention will be fully understood from the following description, when taken in connection with the annexed drawings, in which— 30 Figure 1 represents a perspective view of a portion of a board fence employing my improved post; Fig. 2, a similar view of a portion of a wire fence; Fig. 3, a side elevation of a post; Fig. 4, a detail view of the blank from 35 which the post is rolled or stamped; Fig. 5, a cross-section of the post; Fig. 6, a detail view of one wing of the anchor detached.

The post is formed of a single strip or plate of sheet metal, formed into shape while hot by 40 suitable tools and appliances.

In the drawings, the letter A designates the post, which is rolled or pressed into practically a Z form in cross-section, having the longitudinal flanges *a a* and the plain flat surface 45 *b*, these flanges or surface being perforated at suitable intervals for the passage of the attaching wires of the fence, as clearly shown in Figs. 1 and 2. The post is sharpened at its lower end, as at *c*, to facilitate its passage into 50 the earth, and is preferably formed slightly tapering. The lower ends of the flanges *a a* are somewhat extended, forming tongues *a' a'*, as shown in Fig. 4. These tongues are bent upward and outward at *c*, and then inward

again at *d*, terminating against the outer face 55 of the flanges, and form wedge-shaped anchors *B B* upon opposite sides of the post. These anchors are so shaped that they will not prevent the post from being driven into the ground, but will prevent its withdrawal when once inserted into the earth. The post as thus constructed may be made very light and strong, and, particularly if treated with a coat of coal-tar or other preservative, will be very durable. The post is simple and inexpensive in 60 construction; but it answers all purposes for which such devices are intended.

We may find it advisable to cast this post, and in that case we may make the anchors *B B* separate, as shown in Fig. 6, and bolt or 70 rivet them on; or we may cast them integral, as the exigencies of the case may require.

Having thus fully described our invention, what we claim as new, and desire to secure by Letters Patent, is—

75

1. A fence-post consisting of a single piece of sheet metal pressed or rolled into Z form in cross-section, one of the flanges of the said post being perforated for the passage of the tie-wires of the fence, substantially as described.

2. A fence-post consisting of a single piece of sheet metal pressed into Z shape in cross-section, one of the vertical flanges or faces of the post being perforated and the lower end of 85 the post sharpened, substantially as herein set forth.

3. A fence-post formed out of a single piece of sheet metal pressed into Z-shaped form in cross-section, the longitudinal flanges *a a* of 90 the said post being provided with tongues *a' a'*, these tongues being bent upward and outward and then inward toward the faces of the said flanges, forming the anchors *B B* on opposite sides of the post, substantially as herein 95 set forth.

4. A metallic fence-post, A, formed Z shape in cross-section, one of the longitudinal faces or flanges of this post being perforated, and the wedge-shaped anchors *B* upon opposite 100 sides of the said post, substantially as described.

In testimony whereof we affix our signatures in presence of two witnesses.

JASPER M. MADDING.
